UNITED STATES PATENT OFFICE

168,393

JEWELRY CASE OR SIMILAR ARTICLE

Emile A. Bourcart, New York, N. Y.

Application January 9, 1952, Serial No. 17,975

Term of patent 3½ years

(Cl. D86—9)

To all whom it may concern:

Be it known that I, Emile A. Bourcart, a citizen of the United States, residing in the city of New York, Borough of Manhattan, county and State of New York, have invented a new, original, and ornamental Design for a Jewelry Case or Similar Article, of which the following is a specification, reference being had to the accompanying drawing, forming a part hereof:

Fig. 1 is a perspective view of a jewelry case showing my new design, illustrated in closed position;

Fig. 2 is a perspective view thereof, partially opened; and

Fig. 3 is a perspective view of the same, completely opened.

I claim:

The ornamental design for a jewelry case or similar article, substantially as shown.

EMILE A. BOURCART.
